FOLDING BERTH

Edward E. Woller, Kenosha, Wis., assignor to
Simmons Company, New York, N. Y., a corporation of Delaware

Application August 13, 1931. Serial No. 556,805

1 Claim. (Cl. 5—10)

This invention relates to folding berths, sometimes called disappearing bunks, such as are often used in the state rooms of boats and like vessels and in similar places in other vehicles.

- 5 The main object of the invention is to provide a folding berth of the type referred to, which will be comparatively easy to manipulate and which will be firm and rigid in its extended position so as to constitute a safe and comfortable bed.
- 10 Other objects and advantages of the invention will be understood by reference to the following specification and accompanying drawings (three sheets), in which a selected embodiment of the invention is illustrated.

15 In the drawings:

Figure 1 is a perspective illustrating the general arrangement of a folding berth embodying the invention.

Figure 2 is an end elevation partly in section 20 showing the folding berth partly folded.

Figure 3 is a view similar to Figure 2, but showing the parts in folded position.

Figure 4 is a detail showing the manner of connecting one end of a cable to the end of the berth.

25 Figure 5 is a sectional view on the line 5—5 of Figure 1, illustrating a device for locking a part of the structure in open or unfolded position.

Figure 6 is a section on the line 6—6 of Figure 2.

30 Figure 7 is a sectional view showing the construction of a counterbalancing device which is shown in elevation in Figure 6.

Figure 8 is an enlarged view showing a portion of the structure shown in Figure 1, certain parts

35 being broken away and shown in section to more clearly illustrate the structure.

Figure 9 is a section on the line 9—9 of Figure 8.

Figures 10 and 11 are sectional views illustrating certain locking devices for holding the folding parts in folded position.

Referring now to the drawings, I have illustrated in Figure 1 one corner of a state room wherein a bed 15 of any conventional form is positioned in one corner of the room, and a disappearing or folding bed 16 is located in the same corner of the room above the bed 15.

The disappearing bed 16 is designed to be folded into a

45 receptacle 17, which includes end and side walls 18, 19, 20 and 21, respectively, and a top closure 22' which may, if desired, be the ceiling of the state room or a special closure for the bed-receiving receptacle.

The bed 16 may be of any convenient construction and, in this instance, includes a frame 22

which sustains any suitable form of bed spring fabric, upon which a mattress 23 is positioned. Head and foot frames 24 and 25, respectively, are mounted at the head and foot ends of the frame, and a lee or side rail 26 is mounted on the side frame adjacent the head end of the bed. The head frame and lee rail 24 and 26, respectively, are adapted to be folded over the adjacent portions of the mattress, the head frame 24 preferably overlapping the lee rail 26. The foot end frame 25 is also mounted so as to be displaceable into folded position between the mattress and the bed spring fabric carried by the frame 22 or in other suitable position.

The bed bottom 16 is foldably mounted at one side on a panel board 27, a hinge bracket 28 being secured to the panel in any suitable manner for co-operating with the hinge bracket 29 which is carried by the end frame member of the bed frame 22. The hinge members 28 and 29 are pivoted together, as indicated at 30, whereby it will be seen that the bed bottom 16 is foldable relative to the panel 27 from laterally extending bed position, as indicated in broken lines in Figure 2, to partially folded position substantially parallel with the panel, as shown in full lines in Figure 2. Of course, it will be understood that a similar pivotal connection is provided at both ends of the bed bottom.

The panel 27 is foldably connected by means of a hinge structure 31 adjacent its upper edge to the receptacle side member 19. By virtue of the pivotal connection 31 between the panel 27 and the receptacle 19, the panel and the bed bottom 16, when folded to the full line position shown in Figure 2, are adapted to be folded about the pivot 31 into the receptacle 17.

For locking the bed bottom and panel in folded position within the receptacle 17, a spring-pressed latch bar 32 is provided in the receptacle 95 at each end thereof for co-operating with a latch-receiving lip 33 carried by the adjacent side of the panel 27 (see Figures 3 and 10). The latch bar 32 is normally urged into locking engagement with the lip 33 by means of a spring 34, and the latch is adapted to be disengaged through the agency of the knob 35 which is connected to the latch so that the same may be retracted against the pressure of the spring 34, as will be apparent from an inspection of Figure 10.

100 In its unfolded position, as shown in Figure 1, the bed bottom 16 is effectively locked in fixed position relative to the panel 27 and relative to the receptacle 17 by means of a rigid bar 36 which is pivotally connected at its opposite ends 105 110

to the bed bottom, as indicated at 36', and to the end wall 20 of the receptacle. The lower end of the rigid bar 36 is pivotally connected to the bed frame in any suitable manner, and the upper 5 end of the bar 36 is detachably connected to the receptacle wall 20 by means of the disengageable latch device illustrated in Figures 8 and 9.

The supporting bar 26 is preferably of tubular construction and is provided with suitable bearing blocks 37 and 38, respectively, for supporting 10 a locking rod 39 for longitudinal movement within the tubular bar 36. Adjacent the lower bearing member 38, a block or collar 40 is secured to the rod 39 and provided with an end piece 41 which projects outwardly through a slot 42 provided in the tubular bar. A spring 43 interposed between the collar 40 and the bearing member 38 normally urges the rod 39 to move upwardly. The upper end of the bar 36 is provided with an 15 opening adapted to fit over a stud 45 which is suitably secured to the receptacle wall 20. The stud 45 is provided with a groove 46 into which the bar or rod 39 is caused to project so as to prevent displacement of the upper end of the bar 36 from the stud 45. Obviously, displacement 20 may be effected by moving the rod 39 downwardly against the pressure of the spring 43, such movement being effected through the agency of the end piece 41.

It will be understood that the bar 36 by which the outer or free side of the bed bottom is suspended from the receptacle 17 co-operates with the panel 27 to support the bed bottom in operative position. The rigidity of the bar 36 obviously 25 serves to prevent upward swinging of the bed bottom about its pivot 30.

To prevent side sway or swinging of the bed bottom about the pivots 31 and 45, the panel 40 27 is locked at its free end to the wall 47 by means of a locking device 48 at the free side 45 of the panel. (See Figures 1, 2 and 5.) The locking device 48 includes a bracket element 49 which is pivotally secured, as indicated at 50, to the panel 27 adjacent its free side, the bracket 49 having an apertured boss 51 for slidably and 55 rotatably receiving a locking screw 52. The locking screw 52 is provided with screw threading, as indicated at 53, at one end, and with a knob 54 at its other end for facilitating manipulation of the screw which is designed to engage a screw-threaded socket bracket 55 which is secured to the wall in any suitable manner. The apertured boss 51 is counterbored, as shown at 56, to permit the locking screw 52 to be drawn outwardly until the screw-threaded end thereof is entirely within the boss 51, so that the bracket 55 50 may be swung about its pivot 50 so as to be within the area of the panel, whereby the panel may be swung into closed position, as shown in Figure 3. It will be understood that the locking screw 52 is provided with an annular enlargement 57 which co-operates with the knob 54 to anchor the locking screw to the bracket 49, and that the counterboring 56 is provided for receiving said annular enlargement. If desired, 60 the panel 27 may be provided with wear plates, such as indicated at 58, for receiving the locking bolts 52 when the same are swung inwardly as just described.

When it is desired to fold the bed from its extended position, as shown in Figure 1, the corner bar 36 is disconnected from its upper anchorage 45 in the manner described, and the bed bottom swung upwardly about its pivot 30 until it 70 occupies substantially the position shown in full

lines in Figure 2, wherein it is parallel to the plane of the panel 27. Of course, it is understood that the end frames 24 and 25 and the lee rail 26 are first folded over, as previously referred to. For locking the bed bottom 16 in the 80 full-line folded position of Figure 2, a locking device such as illustrated in Figure 11 is provided. This locking device consists of an inverted hook-like bracket 59 which is suitably secured to the panel 27 adjacent its upper or inner edge. Mounted in the bracket 60 which supports one end of the lee rail 26 is a spring-pressed dog 61, this dog being pivotally anchored, as indicated at 62, in the bracket 60 and normally urged outwardly by means of a spring 63.

The outer end of the dog 61 is provided with a hook 64 designed to snap back of the inverted hook bracket 59 to thereby lock the bed bottom 16 in the folded position shown. A button 65 may be provided for facilitating disengagement of the locking dog 64 when it is desired to unfold the bed. The locking dog 64 also serves to lock the lee rail 26 in up position when the bed is extended.

From the full line, partly folded position shown 100 in Figure 2, the bed bottom 16 and panel 27 are adapted to be folded as a unit about the pivot 31 into the receptacle 17 as shown in full lines in Figure 3. The locking device shown in Figure 10 and previously described is then operative 105 to lock the bed in such folded position.

It will be observed that only one corner of the bed is supported in its extended position by a bar such as 36 and that the corresponding corner of the bed at the opposite end thereof 110 is supported by means of a bracket 66 secured to the wall and which may conveniently constitute an electric light bracket as indicated in Figure 1. The bed may be locked to the bracket 66 by any suitable means, if desired, or it may merely 115 rest thereon.

For facilitating folding of the bed in the manner described, counterbalancing means is provided. In this instance, the counterbalancing means is located within the receptacle 17 so as 120 to be practically concealed. The counterbalancing means herein shown is in the form of a pair of spring-controlled rollers designated 67 and 68, respectively, the construction of these rollers being more fully shown in Figure 7. 125

By inspection of Figure 7, it will be seen that there is a central shaft 69 which is anchored against rotation by being mounted at its ends in brackets 70 and 71, the ends of the shafts being provided with flaps, or the like, fitting in 130 corresponding openings in the brackets 70 and 71 which are secured to the ends 18 and 20 of the receptacle 17. The shaft 69 is also supported intermediate its ends, and approximately midway thereof, by means of a bracket 72 which 135 is secured to the ceiling or closure 22' of the receptacle.

At opposite sides of the intermediate bracket 72, there are provided collars 73 and 74, respectively, which are rotatably mounted on the shaft 140 69. At the opposite ends of the shaft 69, there are collars 75 and 76, respectively, which are also rotatably mounted on the shaft 69 and which are respectively connected to the collars 73 and 74 for rotation in unison therewith by means 145 of sleeves or tubes 77 and 78, respectively. Torsion springs 79 and 80 are disposed within the respective tubes 77 and 78 and around the enclosed portions of the shaft 69, one end of each spring being anchored to the shaft as indicated 150

at 81 and 82, while the opposite ends of the respective springs are anchored to the collars 73 and 74, as indicated at 83 and 84, respectively.

Each of the end collars 75 and 76 are provided with spirally cut grooves, such as indicated at 85 and 86, respectively, for receiving cables such as 87 and 88, each of which has one end suitably anchored to the collar on which it is wound.

From the respective collars or drums 75 and 76, the respective cables extend along the inside of the adjacent ends of the receptacle over and downwardly around guide pulleys located intermediate the width of the receptacle, as indicated at 89 in Figure 2, the outer end of each cable being pivotally secured to the adjacent end of the bed bottom frame, as indicated at 90.

The construction of the pivot connection 90 between the cable and the bed frame 22, is shown in Figure 4. By examination of Figure 4, it will be seen that the end of the cable is anchored in a bracket plate 90, which plate is secured to an anchor block 91. The anchor block 91 is provided with a recess 92 for receiving a headed pivot pin 93 which is rigidly secured to the bed frame 22, as clearly shown in said Figure 4.

When the bed is in extended position as shown in Figure 1 (and as shown in dotted lines in Figure 2), the cables 87 and 88 are, of course, unwound from the respective drums or reels 75 and 76, and the counterbalancing springs 79 and 80 are wound sufficiently to counterbalance the weight of the bed bottom and panel. Obviously, the spring counterbalancing arrangement described serves to facilitate manipulation of the folding bed structure by relieving the operator of the necessity of handling the entire weight of the folding structure, whereby the operation of the

folding bed is greatly facilitated and the labor necessary to expend in such operation is greatly reduced.

The arrangement of the counterbalancing means within the receptacle, as described, is highly desirable in that it is practically out of sight, whereby the neatness of appearance of the structure is not impaired and whereby it is out of the way and not apt to be damaged by engagement with various parts of the folding structure, or otherwise.

I am aware that changes may be made in the described structure without departing from the spirit of the invention, the scope of which should be determined by reference to the following claims, the same being construed as broadly as possible consistent with the state of the art.

I claim as my invention:

In a folding berth of the class described, the combination of a downwardly facing receptacle, a panel pivotally connected at one side to said receptacle and foldable from closed position to open position wherein the panel extends downwardly from said receptacle and substantially parallel to an adjacent wall, a bed bottom foldably secured to said panel and means for locking the free edge of said panel to said wall when the bed is extended, said means including a bracket and a locking member, the bracket being pivoted to said panel adjacent said free edge and adapted to extend beyond said free edge for engagement with the wall, the bracket being pivotally adjustable from said position to a position within the area of the panel to thereby position said locking bracket within the area of said receptacle when the panel is folded to closed position.

5 with spirally cut grooves, such as indicated at 85 and 86, respectively, for receiving cables such as 87 and 88, each of which has one end suitably anchored to the collar on which it is wound.

From the respective collars or drums 75 and 76, the respective cables extend along the inside of the adjacent ends of the receptacle over and downwardly around guide pulleys located intermediate the width of the receptacle, as indicated at 89 in Figure 2, the outer end of each cable being pivotally secured to the adjacent end of the bed bottom frame, as indicated at 90.

The construction of the pivot connection 90 between the cable and the bed frame 22, is shown in Figure 4. By examination of Figure 4, it will be seen that the end of the cable is anchored in a bracket plate 90, which plate is secured to an anchor block 91. The anchor block 91 is provided with a recess 92 for receiving a headed pivot pin 93 which is rigidly secured to the bed frame 22, as clearly shown in said Figure 4.

When the bed is in extended position as shown in Figure 1 (and as shown in dotted lines in Figure 2), the cables 87 and 88 are, of course, unwound from the respective drums or reels 75 and 76, and the counterbalancing springs 79 and 80 are wound sufficiently to counterbalance the weight of the bed bottom and panel. Obviously, the spring counterbalancing arrangement described serves to facilitate manipulation of the folding bed structure by relieving the operator of the necessity of handling the entire weight of the folding structure, whereby the operation of the

folding bed is greatly facilitated and the labor necessary to expend in such operation is greatly reduced.

The arrangement of the counterbalancing means within the receptacle, as described, is highly desirable in that it is practically out of sight, whereby the neatness of appearance of the structure is not impaired and whereby it is out of the way and not apt to be damaged by engagement with various parts of the folding structure, or otherwise.

I am aware that changes may be made in the described structure without departing from the spirit of the invention, the scope of which should be determined by reference to the following claims, the same being construed as broadly as possible consistent with the state of the art.

I claim as my invention:

In a folding berth of the class described, the combination of a downwardly facing receptacle, a panel pivotally connected at one side to said receptacle and foldable from closed position to open position wherein the panel extends downwardly from said receptacle and substantially parallel to an adjacent wall, a bed bottom foldably secured to said panel and means for locking the free edge of said panel to said wall when the bed is extended, said means including a bracket and a locking member, the bracket being pivoted to said panel adjacent said free edge and adapted to extend beyond said free edge for engagement with the wall, the bracket being pivotally adjustable from said position to a position within the area of the panel to thereby position said locking bracket within the area of said receptacle when the panel is folded to closed position.
